UNITED STATES PATENT OFFICE.

HERMAN G. WALKER, OF OAKLAND, CALIFORNIA.

WINDOW VENTILATOR FRAME.

Application filed February 6, 1928. Serial No. 252,095.

The invention forming the subject matter of this application relates to window ventilators.

The primary object of the invention is 5 the provision of a window ventilator frame of an improved construction, which may be readily secured to a window frame and which securely supports a deflector in such a manner as to obviate any possibilities of 10 noise and rattle incident to air impact.

Another object of the invention is to provide a window ventilator frame which is highly useful and simple in construction. Convenience of arrangement, lightness and 15 comparative inexpense of manufacture are further objects which have been borne in mind in the production and development of the invention.

With the above and other objects in view 20 my invention resides in the combination and arrangements of parts hereinafter described and claimed, it being understood that changes in the precise embodiment of the invention hereinafter disclosed may be made 25 within the scope of the appended claims, without departing from the spirit of the invention.

The invention is clearly illustrated in the accompanying drawings, in which

30 Figure 1 is a front view of the device showing the same attached to a window frame,

Figure 2 is a cross sectional view of the window ventilator deflector as attached to 35 a window frame, the section being taken along the line 2—2 of Figure 1, and shown on an enlarged scale, and

Figure 3 is a sectional plan view of my 40 device taken on the line 3—3 of Figure 2.

Referring to the accompanying drawing 45 wherein similar reference characters designate similar parts throughout, the various figures described above adequately illustrate my invention, and the following detailed description is commensurate with the above mentioned drawing in enabling an artisan to construct and assemble the constituent parts of the same.

In carrying out my invention, I make 50 use of end plates designated by the numeral 5, said end plates having angularly disposed deflector supports 6 thereon. The deflector supports 6 are integral parts of the end plates 5 and are bent at right angles thereto. 55 Tongues 7, preferably of rectangular shape, are bent out of the end plates 5 in such a

manner that one side of the rectangular tongue remains integral with the end plates 5 while the outer edge of the tongue is bent away from said end plates into a position 60 opposite to and in parallelism with the angularly disposed deflector support 6. Although in the illustration three tongues 7 are shown on each end plate 5, the number of tongues may vary in accordance with 65 practical requirements.

A deflector plate 8 is adapted to be slipped between the deflector support 6 and the tongues 7 so that the ends of the deflector plate rest upon the angularly disposed supports 6.

The deflector plate 8 is provided with tongues 9 punched out of the deflector adjacent to and spaced from the end thereof, so that when the deflector is disposed upon 75 the supports 6 the tongues 9 are in registry with the tongues 7 on the end plates 5. The tongues 9 are preferably rectangular, one side thereof being integral with the deflector 8. The free end of each tongue 9 is 80 bent out of the plane of the deflector in such a manner as to resiliently press against the bent end of the prongs 7, when the ventilator is assembled.

Before the ventilator is assembled, the end 85 plate may be inserted between a window casement 11 and the window stop 12 as it is clearly shown in Figure 1. The end plates 5 are provided with a hole 13 permitting the insertion of a screw 14 therethrough which 90 screw extends through the window stop 12 and into the window casement 11, thus securing the end plates in place. After the end plates are firmly secured to the window casement the deflector 9 is inserted in place so 95 that the ends thereof rest against the deflector support 6 while the tongues 9 thereof are brought in registry with the tongues 7 on the respective end plate. During the assembly a certain amount of force is required 100 to slide the tongues 9 below the tongues 7 so that the frictional engagement between the complementary tongues firmly holds the deflector in place thereby obviating any possibility of noise or rattle due to the impact of 105 air.

Although a deflector is shown with tongues 9 thereon for the engagement of the complementary tongues 7 on the plates 5, it is to be noted, that any standard deflector such as a glass plate, wood or metal plate 110 could be inserted between the deflector sup-

port 6 and the tongues 7. A considerable variation as to the thickness of the deflector is permitted because of the fact that the spacing between the deflector support 6 and the bent ends of the tongues 7 may be readily adjusted by simply bending the tongues 7 so as to change the angular position thereof. The tongues 7 must be so bent that the space between the ends thereof and the deflector support 6 is slightly smaller than the thickness of the deflector, so that the deflector is held firmly in place by the resilient pressure exerted thereon by the metal tongues 7.

It is also to be noted that the tongues may be of any desirable shape, such as triangular or polygonal, as long as they present an outside edge or point which is adapted to exert resilient pressure upon a deflector plate with or without complementary tongues thereon, thereby resiliently pressing the same against the deflector support 6, thus holding the same in position with sufficient firmness to prevent any vibration thereof.

In manufacturing the device while the various elements thereof may be constructed in any suitable manner and of any suitable material, yet it is preferable to form the same from sheet metal stampings on account of the cheapness, lightness and strength of the latter; but irrespective of these features in manufacturing the essential features of the invention are always preserved.

Having thus described my invention, what I now claim as novel and desire to secure by Letters Patent is:

1. In a window ventilator, two end brackets adapted to be secured to a window, an angularly positioned deflector support on each bracket, tongues extending from said end brackets toward said deflector supports, a deflector plate disposed on said supports, and means on the ends of the deflector plate to cooperate with said tongues for pressing the ends of the deflector plate against said support.
2. In a window ventilator, two end brackets adapted to be secured to a window, an

angularly positioned deflector support on each bracket, tongues bent out of said bracket and extending opposite said support; a deflector plate frictionally secured between said supports and said tongues, an edge of each bracket being adapted to be inserted between a window stop and a window casing.

3. In a window ventilator, two end brackets adapted to be secured to a window, an angularly positioned deflector support on each bracket, resilient tongues bent out of said bracket and extending opposite said support; a deflector plate frictionally secured between said supports and said tongues, an edge of each bracket being adapted to be inserted between a window stop and a window casing; and means extending thru the window stop and thru the bracket into the window casing for securing the bracket in place.

4. In a window ventilator, two end brackets adapted to be secured to a window; an angularly positioned deflector support on each bracket; tongues bent out of said bracket and extending opposite said support; a deflector plate, tongues on said deflector plate being complementary to said bracket tongues, said deflector plate being held in position by the pressure of said complementary tongues upon each other.

5. In a window ventilator, two end brackets adapted to be secured to a window; an angularly positioned deflector support forming an integral part of each bracket; resilient tongues integral with said brackets, the free end of said tongues being disposed opposite said support; a deflector plate resting upon said supports, resilient tongues integral with said deflector plate and being complementary to said bracket tongues, said deflector being frictionally held in place by the engagement of the free end of the complementary tongues.

In testimony whereof I affix my signature,

HERMAN G. WALKER.
